UNITED STATES PATENT OFFICE.

LOUIS WINTERBAUER, OF NEW YORK, N. Y.

BEER APPARATUS.

SPECIFICATION forming part of Letters Patent No. 259,625, dated June 13, 1882.

Application filed April 4, 1882. (No model.)

To all whom it may concern:

Be it known that I, LOUIS WINTERBAUER, a citizen of the United States, residing at New York, in the county and State of New York, 5 have invented new and useful Improvements in Apparatus for Supplying and Recovering Carbonic-Acid Gas, of which the following is a specification.

The object of this invention is to produce an 10 apparatus which shall answer the dual purpose of supplying carbonic-acid gas to beer-barrels on tap and of recovering such gas when the beer has been drawn off. It has been common heretofore to supply carbonic-acid gas to 15 beer-barrels, but no provision has been made for recovering such gas, it being allowed to escape, and hence a loss or waste is incurred, which is obviated by my invention.

This invention is illustrated by the accompanying drawings, in which Figure 1 represents a front view, partly in section. Fig. 2 is a cross-section on the line *x x*, Fig. 1. Fig. 3 is a detail.

Similar letters indicate corresponding parts. 25 The letter A designates a reservoir or tank of ordinary form for containing the carbonic-acid gas, and B a service-pipe emanating from the reservoir.

C indicates a receiver embodying in its 30 structure a suction-valve, D, and discharge-valve E, similar in construction and arrangement to pump-valves; F, a return-pipe terminating in the suction-valve of the receiver.

H denotes a two-way cock, having connected 35 therewith both the service-pipe B and return-pipe F, such connection being made through branches B' F', Fig. 2. In applying the apparatus to use this cock H is connected to the barrel containing the beer—as, for example, 40 by a flexible tube, I, and spigot J, Fig. 2—and when the cock is turned to the position shown in Fig. 2 the service-pipe B is opened and gas is supplied to the barrel from the reservoir A, while when the cock is turned to another position 45 the return-pipe F is opened and the gas is conducted back from the barrel to the receiver C, into which it passes through the suction-valve D—namely, by displacing the valve, either pipe being closed when the other is 50 opened.

In practice the return-pipe F is opened when

all the beer has been drawn from the barrel, and by its means I recover or obtain not only the gas which has been supplied to the barrel, but also that which has been generated by the 55 beer, except that portion which has escaped with the beer.

The gas passes from the receiver C into the reservoir A through the discharge-valve E, and in order to overcome or provide for an excess of pressure in the reservoir I combine with the receiver a pumping attachment operating to forcibly eject the gas. This attachment consists, in the example shown, of a water-cock, K, which is connected to the lower part of the receiver and through which water is admitted thereto under pressure at the proper time, so that as the water rises in the receiver it compresses and displaces the gas. Another effect of this attachment is that when the water is 70 permitted to escape a partial vacuum is produced in the receiver, whereby the gas is drawn into it from the barrel. The water-cock K is a desirable contrivance, because the required purpose can thereby be accomplished by simply connecting it with a water-supply faucet in a building; but a piston or other equivalent means also can be used, the receiver being in either case converted into a pump. 75

In the branch B' of the service-pipe are arranged two valves, N O, (see Fig. 2,) both having a common chamber, P. The valve N is a check, serving to prevent the beer from rushing from the barrel through the service-pipe B to the reservoir by effervescence, and such 80 valve is supported by a spiral spring, r, resting on the bottom of the chamber P. The valve O is a regulating device for determining the pressure of the gas supplied to the barrel, and it is supported by an elastic diaphragm, s, having combined therewith a spring, t, whereby the valve is held open against a fixed pressure of the gas, while when its pressure rises the valve is permitted to close, due to the action of the gas. 85 90

In the return-pipe F is arranged a suction-valve, U, Fig. 1, and when the barrel has been entirely emptied of the gas by the action of the receiver pumping attachment this valve opens automatically and admits air, thus preventing the creation of a vacuum in the barrel. I arrange the suction-valve U in a hori- 95 100

zontal portion of the return-pipe and below the plane of its inner surface, so that the valve remains closed while the gas is being drawn from the barrel.

5 In the branch F' of the return-pipe is arranged a stop-cock, V, whereby this pipe can be shut off irrespective of the main or two-way cock.

If desired, the pipes B F may be connected 10 with the spigot J independently of each other, in which case two cocks, B' F', are used, one to each pipe.

What I claim as new, and desire to secure by Letters Patent, is—

15 1. The combination, substantially as hereinbefore described, of the gas-reservoir, the service-pipe emanating from the reservoir, the receiver having a suction-valve and discharge-valve, the return-pipe terminating in the suction-valve of the receiver, and the coupling-pipe extending from the discharge-valve of the receiver to the reservoir.

20 2. The combination, substantially as hereinbefore set forth, of the receiver having a suction-valve and discharge-valve and the pumping attachment of the receiver with the reservoir, the coupling-pipe, the service-pipe, and the return-pipe.

25 3. The combination, substantially as hereinbefore described, of the receiver having a suction-valve, discharge-valve, and water-cock

with the reservoir, the coupling-pipe, and the return-pipe.

4. The combination, substantially as hereinbefore set forth, of the service-pipe, the return-pipe, and the two-way cock having both pipes connected thereto with the reservoir, the receiver having a suction-valve and discharge-valve, the coupling-pipe extending from the discharge-valve of the receiver to the reservoir, the service-pipe emanating from the reservoir, and the return-pipe terminating in the suction-valve of the receiver. 40

5. The combination, substantially as hereinbefore set forth, of the service-pipe having arranged therein the check-valve N, the gas-pressure regulating valve O, and the chamber common to both such valves with the reservoir and receiver. 45

6. The combination, substantially as hereinbefore set forth, of the return-pipe and the suction-valve arranged therein with the receiver having a suction-valve and discharge-valve, the return-pipe connected to the suction-valve, and the pumping attachment of the receiver. 50

In testimony whereof I have hereunto set my hand and seal in the presence of two subscribing witnesses.

LOUIS WINTERBAUER. [L. S.]
